UNITED STATES PATENT OFFICE

EDWARD LAWRENCE HIGGINS, OF SIDCUP, ENGLAND

PERMUTATION LOCK

Application filed April 17, 1926, Serial No. 102,681, and in Great Britain May 13, 1925.

This invention relates to permutation locks or the like and has for its object to provide an improved device of this character which will give a high degree of security against 5 unauthorized manipulation.

According to the invention a combination or permutation lock is provided wherein a number of rotatable locking members mounted co-axially on a slidable element are formed 10 with means to prevent axial movement of the slidable element which is adapted to be released and allow the lock to be opened when all the locking members occupy pre-arranged positions. According to the preferred form 15 of the invention a number of rotatable locking members co-operate with a slidable element adapted to act as or engage the lock bolt to lock the slidable element against movement in all but one pre-arranged position of the rotatable members which are rotated by a device in which the unlocking combination of letters or numerals can be varied at will.

Reference will now be made to the accompanying drawings in which:—

Figure 1 is a sectional elevation of a lock constructed according to one form of the invention,

Figure 2 is a section on the line A B of 30 Figure 1,

Figure 3 is a section on the line C D of Figure 1,

Figure 4 is a longitudinal section through a lock constructed according to another form 35 of the invention,

Figure 5 is a section on the line E F of Figure 4,

Figure 5A is a section similar to Figure 5 with leaf spring in section.

Figure 6 is a view showing the application of the lock shown in Figures 4 and 5 to a window frame,

Figure 7 is a section on the line G H of Figure 6,

Figure 8 is a view in elevation showing a modified form of the lock shown in Figures 4 and 5 applied to a door, and

Figure 9 is a plan of the lock shown in Figure 8.

50 The lock shown in Figures 1-3 comprises

two side plates, 1, 2 secured together to form a casing which contains a sliding bolt 3 actuated by an external handle 4 fixed to a lever 5 which has a pin and slot connection with the bolt.

The bolt 3 slides between the plate 2 and a partition plate 6 fixed in the casing, and is adapted to be locked in either of two positions by means of a sliding bar 7 which can be engaged in either of two recesses 8 formed in the bolt 3. The bar 7 is formed with a number of pins or projections 9 which engage in annular recesses in locking discs 10 which are mounted coaxially on the bar 7 between the plates 1 and 2, the pins or projections 9 being free to move through slots or apertures formed in the discs 10 when each of these discs is adjusted to bring its slot or aperture into line with the corresponding pin or projection 9.

The bar 7 is adapted to be actuated by an external handle 11 and in order to prevent the pins or projections 9 from being sheared by forcing the handle 11, the bar 7 is connected to the handle 11 through a coiled spring 12 which is disposed within the bar 7 and acts between one end of the bar and a piston 13 fixed to a rod 14 which carries the handle 11. The piston 13 normally bears against a block 15 fixed in the end of the bar 7 and the parts are so designed that any inward pressure applied to the handle 11 is taken through the block 15 by the bolt 3 and not by the pins or projections 9 whilst an outward pull on the handle 11 brings the shoulder 16 on the rod 14 against the bottom of a recess 17 in the plate 1 before the spring 12 is fully compressed. The rod 14 is rotatable in the bar 7, but the bar 7 is prevented from rotating by means of a projection 18 which engages a slot in the plate 6.

The locking discs 10 are closely fitted between the plates 1 and 6 and are provided each with an annular ring 20 formed with gear teeth 21 which is rotatably mounted on 95 the locking disc 10 and carries a pawl 22 engaging ratchet teeth 19 on the locking disc.

The plate 1 carries an external cylindrical casing 23 which contains a series of rings or discs 24 equal in number to the locking discs 100

10 and each marked on its external surface with letters or numerals up to any desired number any one of which can be made to register with a viewing aperture 25 in the casing 23. Each of the rings 24 is provided with internal teeth 26 in number equivalent to the number of letters or numerals above described and adapted to engage an arm 27 fixed to a concentric rotary shaft 28 which is mounted to slide in bearing apertures in the ends of the casing 23 so that the arm 27 can be brought into engagement with the teeth 26 of any one of the rings 24. The inner end of the shaft 28 carries a gear 29 adapted to engage the rings 20 the teeth on which agree in number with the numerals or the like on the discs 24, the arrangement being such that when the gear 29 is in mesh with any one of the rings 20, the arm 27 is in engagement with the teeth 26 of the corresponding ring 24. In order to prevent rotation of the shaft 28 when the gear 29 and arm 27 are in intermediate positions between adjacent rings 20 and 24 and to ensure proper registration of the parts, a number of pins 30 fixed to the casing of the lock are adapted to engage between the teeth of the gear 29 when it is in intermediate position between the rings 20. The positions of the rings 24 are thus made dependent upon the positions of the rings 20. In order to facilitate the correct positioning of the shaft 28, this shaft is provided with a series of annular recesses 31 which co-operate with a spring pressed plunger 31^a adapted to hold the shaft yieldably in any one of its working positions.

The rings 20 drive the locking discs 10 in an anti-clockwise direction (Figure 1) through the pawl 22, and in order to prevent reverse rotation of the rings 20, which would cause the pawls 22 to ride on the ratchet teeth 19 on the locking discs 10, each of the rings 20 engages a spring loaded pawl 32 carried by the casing of the lock. Relative rotation of the rings 20 and locking discs 10 may however, be effected for the purpose of changing the combination of the lock, and for this purpose a crank or cam shaft 33 is provided, which is journaled in holes in the plates 1 and 6 and is formed at its outer end with a slot 34 to enable it to be rotated by means of a screw driver, coin or like implement. The shaft 33 engages each of the pawls 32 and also engages a spring pressed plunger 35 mounted in a recess in the plate 6, and adapted to enter a hole 36 in the bar 7 when the latter is in a position intermediate its extreme positions and such that the pins or projections 9 engage the slots or apertures in the locking discs 10. In the position shown in the drawings the pawls 32 are in engagement with the rings 20 and the plunger 35 is retracted by its spring but the cam shaft 33 is so shaped that when the bar 7 is moved to a position intermediate its extreme positions to

bring the hole 36 in line with the plunger 35, rotation of the shaft 33 will lift the pawls 32 and press the plunger 35 into the hole 36.

The operation of the lock is as follows:— Assuming that the bar 7 is locked in the position shown, to release the bar, the operator moves the indicating discs 24 successively by manipulating the shaft 28 so as to set up the correct combination of letters visible through the apertures 25. When the correct combination is thus set up, the locking discs 10 will each have been brought to a position in which its slot or aperture is in line with the corresponding pin or projection 9 on the bar 7, thus rendering the bar 7 free to be retracted by means of the handle 11. The bar 7 is now retracted and the bolt 3 is then moved to the desired position. In order to lock the bolt in its new position, the bar 7 is moved into engagement with one of the apertures 8 by pushing the handle 11 and the combination is then broken up by moving each of the rings 24 at random. If it is not desired to lock the bolt 3 however, the combination may be broken up with the bar 7 in retracted position, thus preventing unauthorized persons from locking the bolt.

If it is desired to change the combination of the lock, the discs 24 must first be set to the correct combination to release the bar 7. The latter can then be moved to a position intermediate its extreme positions, so that the hole 36 is in line with the plunger 35. The shaft 33 is then rotated by means of a coin or other convenient implement thus lifting the pawls 32 and pressing the plunger 35 into the hole 36 so that the bar 7 is locked in the intermediate position. The rings 20 are now free to rotate in clockwise direction (Figure 1) and can thus be moved into any desired positions by rotating the shaft 28. The rings 24 however, will be adjusted correspondingly, and as the pins or projections 9 have been brought into engagement with the slots or apertures in the locking discs 10 any combination to which the discs 24 may be set will be the correct combination for releasing the bar 7, when subsequently the shaft 33 is returned to its original position. When the rings 24 have been set to the desired new combination, the shaft 33 is returned to its original position so that the pawls 32 are brought into engagement with the rings 20 and the plunger 35 is retracted by its springs. The bar 7 is now moved to locking or release position as desired and the combination is broken up by manipulating the shaft 28. The plunger 35 prevents rotation of the shaft 33 except when the bar 7 is in the intermediate position.

Should the indicating discs 24 or casing 23 become damaged it may be desirable to be able to set the discs 10 to the correct combination without being able to see the letters on the discs 24. This may also be desired in

order that the lock may be opened in the dark. In order to make this possible it is preferred to provide each of the rings 20 with one tooth 21^a which is wider than the others and engages a projection 21^b on the corresponding pawl 32 so as to prevent the pawl from engaging between the teeth 21 at one point. When the discs 10 are being adjusted the movement of the pawls 32 can be heard and the tooth 21^a and projection 21^b, by preventing movement of the pawl 32 at one point provides a "silent spot" which enables the discs 10 to be set by ear. This "silent spot" may conveniently be arranged to correspond with the letter *z* for example, so that when the operator reaches the "silent spot" he knows that the position of the disc 10 under adjustment corresponds to the position of the disc 24 in which the letter *z* is showing. He then has only to count the letters or numbers by the clicks of the pawl 32 to set the disc 20 to the correct position without being able to see the indications on the disc 24.

In the form of construction shown in Figure 4 the lock comprises a barrel or casing 37 containing a non-rotatable sliding bolt 38 formed with pins or projections 39 which engage in annular recesses in a number of locking discs 40 each of which is formed with a slot or aperture 41 through which the pins 39 are free to move when each of the discs 40 is adjusted to bring its slot or aperture into line with the corresponding pin.

The discs 40 are freely rotatable on the bolt 38 and are closely fitted between the ends of the barrel 37 and each disc carries a ring 42 (one of these rings being shown in elevation in Figure 4) which is rotatable on the disc but is frictionally held in an adjusted position with respect to the disc by means of a leaf spring 44^a which engages in an annular groove 44 formed in the outer cylindrical surface of the disc. Each of the flanged members is provided with a milled portion 45 whereby it can be rotated by hand through a slot 46 in the casing and carries a number of numerals or other markings 47 which cooperate with viewing apertures 48 in the barrel 37. The rings 42 are further formed with shallow grooves 49 which engage the ends of spring pressed plungers 50 carried by the barrel 37 and serving to hold the members 42 yieldably in any position in which one of the numerals 47 is correctly positioned in register with the corresponding viewing aperture 48.

In operation the bolt 38 is normally prevented from axial movement by the engagement of the pins 39 in the annular recess of the discs 40, but when the discs are adjusted to show the right combination of numbers through the viewing aperture 48 the pins 39 are free to move through the slots 41 in the disc 40 and the bolt 38 can therefore be moved axially. The bolt has two extreme positions

in which the pins 39 engage in the annular recesses in the discs 40, but when the members 42 are set to the correct combination the bolt can be moved to an intermediate position in which each of the slots 41 in the disc 40 engages one of the pins 39 on the bolt 38. If the bolt is held in this position, rotation of the rings 42 by hand will not cause the discs 40 to rotate but will bring the members 42 into new positions with respect to the discs 40. The combination required to release the bolt can therefore be changed at will.

Figures 6 and 7 show a lock similar to that shown in Figure 4, applied to a casement window. The barrel 37, which is similar to that described with reference to Figure 4, is formed integral with a bracket 51 which is secured to the frame of the window 52 by means of a bolt 53 and screws 54. The bolt 38 of the lock engages in a socket or keeper 55 secured in the window frame.

The lock shown in Figures 8 and 9 comprises a casing 56 adapted to be fitted to or morticed in a door 57, and containing a sliding bolt 58 formed with a wedge surface 59 adapted to co-operate with a corresponding surface on a keeper (not shown) in the door frame so that the bolt is actuated automatically when the door is closed in the well known manner. The bolt is normally held in the position shown in the drawings, by means of a leaf spring 60 disposed in the casing 56 and is controlled by a hand lever 61 fulcrumed to the door at 62 and connected to the bolt 58 through a slot 63 in the casing 56. A barrel 37 similar to that described with reference to Figure 4 is secured in to the casing 56 and contains a bolt 38 which can be moved into or out of the path of the bolt 58 so as to lock this bolt in the position shown in the drawings or to permit it to be moved against the action of the spring 60.

Although a number of different applications of locks constructed according to the invention are shown, it is to be understood that the invention is not limited to these applications and that permutation or combination locks according to the invention can be designed or adapted to any of the many different purposes for which such locks commonly are or may be employed. Moreover the construction of the lock proper may also be varied in many ways.

I claim:—

1. A combination or permutation lock, including a bolt, a slidable element, a plurality of rotatable locking members mounted coaxially thereon, means for permitting axial movement of said element in and out of engagement with said bolt in pre-arranged positions of said locking members, a series of rotary indicating members, and a rotary actuating member axially adjustable to bring it into engagement with any one of said locking members and simultaneously with the

- corresponding one of said indicating members whereby the positions of the locking members are made dependent upon the positions of the indicating members.
2. A lock according to claim 1, wherein said indicating members are visible through the casing of the lock and adapted to be actuated by hand through a slot provided in said casing.
3. A lock according to claim 1, including an external actuating member and a resilient connection between the same and said sliding element.
4. A combination or permutation lock, including a bolt, a slidable element, a plurality of rotatable locking members mounted coaxially thereon, means for permitting axial movement of said element in and out of engagement with said bolt in prearranged positions of said locking members, a series of rotary indicating members, and a rotary actuating device axially adjustable to interconnect corresponding units of said locking and indicating members, and means for securing said locking members against rotation while rearranging the combination.
5. A combination or permutation lock, including a bolt, a slidable element, a plurality of rotatable locking members mounted coaxially thereon, means for permitting axial movement of said element in and out of engagement with said bolt in prearranged positions of said locking members, a series of rotary indicating members, and a rotary actuating device axially adjustable to interconnect corresponding units of said locking and indicating members, and ratchet mechanism interposed between said actuating device and said locking members to secure the latter against rotation while permitting rotation of said actuating device for changing the combination of the lock rotation of said device.
6. A combination lock according to claim 5, including means for locking said slidable element in a position in which pins of said element engage slots in said locking members to secure the latter against rotation.
7. A lock according to claim 5, including pawls for normally securing said locking members against rotation in one direction, a cam for releasing said pawls, and a plunger adapted to engage the lock bolt while in intermediate position.
8. A lock according to claim 1, wherein said locking members carry indicating members which are rotatably mounted on the locking members and are held frictionally in adjusted positions with respect to such locking members in such a manner that the combination of the lock can be changed by rotating the indicating members on the locking members when the slots or recesses in the locking members are in engagement with the pins or projecting on the sliding rod or bar.
9. A permutation or combination lock comprising a casing, a sliding bolt mounted in said casing, a sliding rod or bar mounted in said casing and adapted to be moved into and out of engagement with said bolt by means of an external actuating handle, a number of locking members rotatably mounted coaxially on said sliding rod or bar and provided with slots or recesses co-operating with pins or projections on said bar, a setting device for setting said locking members provided with an external actuating handle and adapted to actuate indicating devices whose positions are made dependent upon the positions of said locking discs.
- In witness whereof I affix my signature.
- EDWARD LAWRENCE HIGGINS.
